UNITED STATES PATENT OFFICE

2,657,445

SLIDER FOR SLIDE FASTENERS

Vitesszav Weber, Cardiff, Wales, assignor to Aero
Zipp Fasteners Limited, London, England, a
British company

Application May 2, 1950, Serial No. 159,485
Claims priority, application Great Britain
May 24, 1949

8 Claims. (Cl. 24—205.14)

1

This invention relates to slide fasteners, and more particularly to an automatically locking slider for slide fasteners.

An object of the present invention is to provide an automatically locking slider which consists of a minimum number of parts which may be readily assembled.

Another object of the present invention is to provide an automatically locking slider which may be manufactured at low costs in mass production.

A further object of the present invention is to provide an automatically locking slider of a construction which lends itself to automatic methods of assembling the individual parts of the slider.

Another object of the present invention is to provide an automatically locking slider which does not require final adjustments of the assembled individual parts.

A further object of the present invention is to provide an automatically locking slider lacking any sharp external corners, which feature is particularly essential for many fields wherein slide fasteners are used.

Another object of the present invention is to provide an automatically locking slider of sturdy construction which is very reliable in use.

A further object of the present invention is to provide an automatically locking slider having a neat appearance.

Another object of the present invention is to improve on the art of automatically locking slide fasteners as now ordinarily made.

Other objects and structural details of the invention will be apparent from the following description when read in conjunction with the accompanying drawings forming part of this specification, wherein:

Fig. 1 is a perspective view of a slider according to the invention;

Fig. 2 is a longitudinal sectional view taken along line II—II of Fig. 1;

Fig. 3 is a sectional view taken along line III—III of Fig. 2;

Fig. 4 is a sectional view taken along line IV—IV of Fig. 2;

Fig. 5 illustrates a piece of metal for making a unit of the slider shown in Figs. 1 to 4;

Fig. 6 is a perspective view of the unit of the slider shown in Figs. 1 to 4;

Fig. 7 is a perspective view of a modified embodiment of a slider according to the invention;

Fig. 8 is a longitudinal sectional view taken along line VIII—VIII of Fig. 7;

Fig. 9 is a sectional view taken along line IX—IX of Fig. 7;

2

Fig. 10 is a longitudinal sectional view, similar to that shown in Fig. 8, however, of another embodiment of a slider according to the invention;

Fig. 11 is a sectional view taken along line XI—XI of Fig. 10;

Fig. 12 is a longitudinal sectional view, similar to that shown in Fig. 8, however, of still another embodiment of a slider according to the invention;

Fig. 13 is a fragmentary perspective view of a detail of the slider shown in Fig. 12;

Fig. 14 is a perspective view of a further embodiment of a slider according to the invention;

Fig. 15 is a longitudinal sectional view taken along line XV—XV of Fig. 14, and

Fig. 16 is a sectional view taken along line XVI—XVI of Fig. 14.

Referring now to Figs. 1 to 6, the slider comprises a slider body generally denoted by reference numeral 1, a structural unit generally denoted by reference numeral 2, and a pull member 3 for operating the slider.

It is understood that in the specification and the appended claims the term "slider body" means the slider without the structural unit and the pull member but including means for securing the structural unit to the slider.

The slider body 1 comprises an upper wing 4 and a lower wing 5 having inturned flanges 6 and 7 respectively, and being joined together in spaced relationship from each other by a neck portion 8 of a wedge-like shape to form a Y-shaped channel 9 between the wings. The upper wing 4 has two windows 10 and 11 and comprises means for securing the unit 2 of the slider body 1. Said securing means include a connecting lug 12 mounted on the upper wing 4 at the wide end of the slider body 1. A stopping lug 13 is mounted on said upper wing 4 at the opposite narrow end of the slider body 1. The connecting lug 12 has lateral recesses 24 and the stopping lug 13 has lateral recesses 42, one such recess being provided at each side of each lug. The connecting lug 12 at the wide end of the slider has, in addition, at its outer surface a central recess or channel 25 leading from the top of the lug 12 into a hole or cavity 26 in the neck portion 8, said cavity 26 being aligned with said channel 25. As can best be seen from Figs. 2 and 3, the lugs 12 and 13 have sloping center portions 27 and 28 respectively which form ribs for strengthening the upper wing 4. The lower wing 5 is provided with a single strengthening rib 29 at its lower surface (see Fig. 2).

The unit 2 comprises an attaching member in the shape of a cap-like yoke 14 having an upper

portion or transverse wall 15 from which two side walls 16 and 17 depend, each having a cut-out 18 extending from the lower edge of the respective side wall upwards for hinging the pull member 3 to the cap 14. The above described construction of the cap-like yoke makes same rigid in its longitudinal direction. Each side wall is provided at one of its ends with a prong 19 and at its opposite end with a prong 91, each prong being rounded off at its tip and extending in the longitudinal direction of the cap 14 so as to be aligned with the respective side wall 16 or 17 and flush with the lower edge thereof. The unit 2 also comprises a flat spring 20, which is bent downwards and forms a tail-like end. Each side wall 16, 17 carries a finger 21 or 22 respectively which extends downwards. The fingers 21 and 22, and the flat spring 20 may be fixed to the cap 14 in any convenient manner. Preferably, however, they are integral with the cap as shown in the drawings. In this case, the unit 2 may simply be manufactured from a piece of metal generally indicated by reference numeral 1023 having the shape illustrated in Fig. 5 and having been punched out from suitable stock material. Subsequently to, or simultaneously with, the punching process, the piece 1023 is bent into shape of unit 2, the portions of the piece 1023 corresponding to the parts 15 to 22 and 91 of the finished unit 2 being indicated by corresponding reference numerals 1015 to 1022 and 1091. It will easily be recognized that owing to its shape the cap is substantially rigid in its longitudinal direction, that is to say it cannot, or cannot easily, be bent around an axis perpendicular to the side walls 16, 17, while the side walls and the prongs 19 and 91 thereon permit some flexing in the direction perpendicular to the said side walls.

The pull member 3 has a lower rim or pivotal portion 23.

In a preferred manner of assembling the slider, the lower rim or pivotal portion 23 of the pull member 3 is inserted into both cut-outs 18 of the cap 14, whereupon the cap is put onto the slider body 1 by passing the locking fingers 21 and 22 through the windows 10 and 11 respectively of the upper wing 4 and simply inserting the prongs 91 at the narrow end of the slider into the recesses 42 of the stopping lug 13. Furthermore, the flat spring 20 is engaged with the channel 25 of the connecting lug 12 and inserted into the cavity 26 of the neck portion 8 and the prongs 19 at the wide end of the slider body 1 are flexed and snapped into position in engagement with the recesses 24 of the connecting lug 12.

The recesses 24 and 42 of the lugs 12 and 13 receive the prongs 19 and 91 respectively with play, so that the cap-like yoke may be tilted from its normal locking position shown in full lines in Figs. 1 and 2 into a releasing position 14' shown in dash-and-dot lines in Fig. 2 and vice versa, while they prevent a disengagement of the prongs from the lugs. The depth of the recesses 24 and 42 is such that the outer surfaces of the prongs 19 and 91 respectively are substantially flush with the outer surfaces of the lugs 12 and 13. When the unit 2 has been secured to the slider body 1, the flat spring 20 of the said unit is received by the central channel 25 of the connecting lug 12, and passes around the upper horizontal portion of said connecting lug 12, then through an angle of substantially 90° and along the vertical portion of the connecting lug 12 to enter the cavity 26 in the neck portion 8, and terminates approximately in the plane of the lower surface of the

upper wing 4 of the slider. The central channel 25 has such a depth that the outer surface of the flat spring 20 is substantially flush with the adjacent outer surfaces of the connecting lug 12. In order to bias the flat spring 20 so as to bear against the bottom surface of the channel 25 and a wall of the cavity 26 when assembled, the spring is originally bent downwards from its horizontal position, shown in Fig. 5, through an angle in excess of 90° as shown in Fig. 6. The locking fingers 21 and 22 pass through the windows 10 and 11 respectively when the unit 2 has been secured to the slider body 1. The fingers 21 and 22 are staggered relatively to one another by the width of a fastener element of a slide fastener in connection with which the slider is intended to be used so as to enable each locking finger normally to engage a space between two adjacent fastener elements, and thereby to lock the slider in its position.

When the slider is used in association with the fastening elements of a slide fastener and a pull is exerted on the pull member 3 of the slider to open or close said slide fastener, the cap 14 is tilted against the action of the spring 20 about the joint formed by the prongs 19 movably engaged with the recesses 24 of the connecting lug 12, so that it reaches the position 14' shown in dash-and-dot lines in Fig. 2. Said tilted position 14' is limited by an abutment of the prongs 91 at the narrow end of the slider against a surface 42a (Fig. 2) of the recess 42 of the stopping lug 13. During such a tilting movement of the cap or attaching member 14, the fingers 21 and 22 are retracted from or lifted out of the Y-shaped channel 9 between the wings 4 and 5 of the slider, whereby the slider is released so as to follow the pull exerted on the pull member.

According to the embodiment of Figs. 7-9, again the upper wing 104 of the slider body 101 is provided with windows 110 and 111 for the passage of the locking fingers (only the finger 122 being shown) normally extending into the slider channel 109. The pull member 103 is linked to the unit 102. The stopping lug 113 having lateral recesses 142 receiving the stopping prongs 191 of the unit 102 at the narrow end of the slider also corresponds to the stopping lug 13 of the embodiment shown in Figs. 1-6.

However, according to Figs. 7-9, the connecting lug 112 arranged at the wide end of the slider does not have lateral recesses. Instead, said connecting lug is provided with flat side walls 124a, wherein indentations 130 of preferably spherical shape are arranged for cooperation with complementary projections 131 on the adjacent prongs 119 of the unit 102 to form a pivot around which the cap 114 of the unit 102 may be tilted when the pull member 103 is operated.

Furthermore, the central channel 125 of the connecting lug 112 merges into an additional channel 1251 in the neck portion 108 of the slider body 101, the additional channel 1251 being in alignment with the central channel 125. The flat spring 120 of the unit 102 is received by the central channel 125, and passes around the upper horizontal portion of the lug 112, then through an angle of substantially 90° and along the vertical portion of the lug 112 and is then received by the additional vertical channel 1251, and terminates at or near the lower surface of the lower wing 105 of the slider. If desired, however, the vertical channel 1251 on the neck portion 108 could be replaced by a cavity similar to the cavity 26 shown in Fig. 2 but extending over substantially the same length as the channel 1251.

5

As best shown in Fig. 8, the cut-outs 118 in the cap 114 of the unit 102 for linking the pull member 103 thereto have sloping walls, and the ribs 127 and 128 of the lugs 112 and 113 are extended towards the middle of the slider into the region of the cut-outs 118, whereby the ribs 127 and 128, and the sloping walls of the cut-outs 118 act as cam surfaces for the rim or pivotal portion 123 of the pull member, and facilitate swivelling or tilting of the unit 102 around its pivot 130, 131 when a pull is exerted on the pull member 103 to open or close the slide fastener.

According to the embodiment of Figs. 10 and 11, the upper wing 204 of the slider body 201 carries again a connecting lug 212 and a stopping lug 213. The stopping lug 213 has lateral recesses 242 receiving the stopping prongs 291 of the cap 214 of the unit 202 with play.

However, as best shown in Fig. 11, projections or protrusions 240 preferably of substantially spherical shape are arranged on each flat side wall 224a of the connecting lug 212 each of said protrusions engaging a hole or recess 241 in the adjacent prongs 219 of the unit 202 to form a pivot around which the unit 202 may swivel when the pull member 203 is operated. The upper horizontal portion of the connecting lug 212 is provided with a central groove 225. The flat spring 220 of the unit 202 is straight and lies substantially in the plane of the upper portion of the cap 214 of the unit 202 at a distance from the upper surface of the upper wing 204 and is received by the groove 225 in the upper outer surface of the lug 212.

On each side of the slider the cut-out 218 (only one cut-out being shown in Fig. 10) in the cap of the unit 202 for linking the pull member 203 thereto has only one sloping wall which lies adjacent to the locking finger, for example locking finger 222, so as to act as a cam surface for the rim or pivotal portion 223 of the pull member 203 when the said pull member is operated to open the slide fastener. The ribs 227 and 228 of the lugs 212 and 213 do not extend into the region of the cut-outs 218 of the unit 202.

According to the embodiment shown in Figs. 12 and 13 the connecting lug 312 and the stopping lug 313 arranged in the slider body 301 have flat side walls.

The prongs 319 of the cap 314 of the unit 302 are provided with protrusions 331 of substantially spherical shape movably engaged with complementary indentations arranged in the said walls of the connecting lug 312.

As shown in Figs. 12 and 13, each of the flat side walls 342a of the stopping lug 313 is provided with a curved elongated indentation 390. Each of the stopping prongs 391 of the cap 314 of the unit 302 is provided with a protrusion 392 movably engaged with the associated indentation 390 of the stopping lug 313.

As best shown in Fig. 12, the connecting lug 312 is provided with a cavity 393 extending in the longitudinal axis of the slider 301. The flat spring 320 representing a continuation of the top transverse wall 315 of the cap 314 is straight and extends in a plane which lies above the pivot 331 of the unit 302 and is spaced from the upper surface of the slider body 301. The flat spring 320 is inserted into the cavity 393 of the connecting lug 312 and bears against a wall of said cavity.

When a pull is exerted on the pull member 303 linked to the unit 302 by its pivotal portion 323

6

engaged with the cut-outs 318 of the cap 314, the unit 302 is tilted upwardly about its pivot 331 until the protrusions 392 on the stopping prongs 391 abut against the upper end of the elongated indentations 390. Upon release of the pull member 303 the unit 302 is automatically returned into its original locking position by the action of the spring 320.

According to the embodiment shown in Figs. 14-16, again the slider body 401 is provided with a connecting lug 412 and a stopping lug 413. The stopping lug 413 is provided with lateral recesses 442 receiving the stopping prongs 491 of the cap 414 of the unit 402 with play.

As best shown in Figs. 15 and 16, the connecting lug 412 comprises a portion 494 having flat side walls 424a and a central channel 425. Furthermore, said connecting lug 412 has a covering portion 495 which during an intermediate step of the manufacture of the slider body 401 is in the position 495' shown in dash-and-dot lines in Fig. 15. After the flat spring 420 has been engaged with the channel 425 during the assembling of the parts of the slider, the covering portion 495 of the connecting lug 412 is bent downwardly from the dash-and-dot line position 495' into the position shown in full lines in Figs. 14-16, whereby the curved cavity 493 is formed. The curved spring 420, then, is housed in said curved cavity 493. Lateral extensions or overhanging portions 444 of the covering portion 495 of the connecting lug 412 cover the upper portion of the prongs 419 of the cap 414 engaged with the side walls 424a of the portion 494 of the connecting lug 412, when the parts are assembled and the covering portion 495 of the connecting lug 412 is bent downwardly.

When a pull is exerted on the pull member 403 linked to the unit 402, said unit may be tilted against the action of the spring 420 about the joint formed by the prongs 419 engaged with the connecting lug 412, until the stopping lugs 491 abut against the surface 442a of the recess 442 of the stopping lug 413.

If desired, the stopping lug 413 could also be made of two parts, similar to the two parts 494 and 495 of the connecting lug 412, one part of which being in an upright position during an intermediate step of the manufacture of the slider and being bent downwardly during the assembling of the elements of the slider.

The slider body according to the invention may be made by casting, molding or coining and swaging.

It should be understood that the terms "upper" and "lower" and the like have been used merely for the purpose of facilitating the description of the invention and refer to the position of the slider and the cap as shown in the accompanying drawings. Of course, the slider may be used in any suitable position.

I have described preferred embodiments of my invention, but it is understood that this disclosure is for the purpose of illustration and that various omissions or changes in shape, proportion and arrangement of parts, as well as the substitution of equivalent elements for those herein shown and described, may be made without departing from the spirit and scope of the invention as set forth in the appended claims.

For example, the tiltable unit of the slider may be provided with one locking finger instead of two locking fingers as shown in the drawings.

Furthermore, the embodiments shown in Figs. 1-6, 10 and 11, 12 and 13, and 14-16 may be pro-

vided with ribs extending into the region of the cut-outs of the cap-like yoke for linking the pull member thereto, whereby the ribs act as cam surfaces similarly as described with reference to the embodiment shown in Figs. 7-9.

Moreover, the cut-outs for linking the pull member to the cap-like yoke of the unit of Figs. 1-6, 12, and 14-16 may each have one or both side walls sloping.

What I claim is:

1. A slider for a slide fastener comprising in combination: a slider body having a Y-shaped channel, an attaching member, a spring, at least one locking finger, said attaching member, spring and locking finger constituting a structural unit, said attaching member being substantially in the shape of a cap-like yoke having two side walls and a transverse wall connecting said side walls and being rigid in its longitudinal direction, said side walls extending in the direction of the longitudinal axis of said slider body, said attaching member being tiltably mounted in said slider body, a pull member linked to said attaching member and through the latter to said slider body, and a lug mounted on said slider body, said locking finger normally extending towards said Y-shaped channel, said spring being in the shape of a flat tail-like spring projecting and extending outwardly from said cap-like yoke, said lug having a second channel at its outer surface, said flat spring being curved towards said slider body, passing around and bearing against the outer surface of said lug, being engaged with said second channel and bearing against the bottom surface of the latter for normally urging said locking finger towards said Y-shaped channel, and said pull member being arranged for acting on a portion of said unit so as to retract said locking finger from said Y-shaped channel against the action of said spring upon exertion of a pull on said pull member.

2. A slider for a slide fastener comprising in combination: a slider body having a Y-shaped channel, an attaching member, a spring, at least one locking finger, said attaching member, spring and locking finger constituting a structural unit, said attaching member being substantially in the shape of a cap-like yoke having two side walls and a transverse wall connecting said side walls and being rigid in its longitudinal direction, said side walls extending in the direction of the longitudinal axis of said slider body, a connecting lug mounted at one end of said slider body, a stopping lug mounted at the opposite end of said slider body, said locking finger normally extending towards said Y-shaped channel, said spring being in the shape of a flat tail-like spring projecting and extending outwardly from said cap-like yoke, said connecting lug having a second channel at its outer surface and two lateral recesses one at each of its sides, said flat spring being curved towards said slider body, being engaged with said second channel and bearing against the bottom surface of the latter for normally urging said locking finger towards said Y-shaped channel; and a pair of prongs, one prong arranged on each side wall of said cap-like yoke, each prong being in movable engagement with a lateral recess of said connecting lug whereby said attaching member is tiltably connected with said connecting lug, said pull member being arranged for acting on a portion of said unit so as to retract said locking finger from said Y-shaped channel against the action of said spring upon exertion of a pull on said pull mem-

ber, and said stopping lug being arranged for co-operation with said attaching member for limiting a tilting movement of the latter by said pull member against the action of said spring.

3. A slider for a slide fastener comprising in combination: a slider body having a Y-shaped channel, said slider body including a first wing, a second wing and a neck portion joining said wings in spaced relationship to each other, a lug mounted on said first wing, said lug having a second channel at its outer surface, said neck portion having a cavity in alignment with said second channel of said lug, an attaching member, a spring, at least one locking finger, said attaching member, spring and locking finger constituting a structural unit, said attaching member being substantially in the shape of a cap-like yoke having two side walls and a transverse wall connecting said side walls and being rigid in its longitudinal direction, said side walls extending in the direction of the longitudinal axis of said slider body, said attaching member being tiltably mounted in said slider body, and a pull member linked to said attaching member and through the latter to said slider body, said locking finger normally extending towards said channel said spring being in the shape of a flat tail-like spring projecting and extending outwardly from said cap-like yoke, said flat spring being curved towards said first wing, being engaged with said second channel, bearing against the bottom surface of the latter, entering said cavity of the neck portion and bearing against a wall thereof for normally urging said locking finger towards said Y-shaped channel, and said pull member being arranged for acting on a portion of said unit so as to retract said locking finger from said Y-shaped channel against the action of said spring upon exertion of a pull on said pull member.

4. An automatic locking slider for a slide fastener, comprising a slider body, a pull member for operating the slider, and a one piece locking unit; the said slider body having opposing shields, and means extending therebetween for connecting said shields in spaced relation to form a Y-shaped channel for the passage of opposing scoop carrying stringers of a slide fastener, a guide channel extending downwardly in said shield connecting means and having side walls and a bottom, cooperating means on said locking unit and said slider body for rockingly connecting said locking unit to said slider body; the said locking unit comprising an open-ended channel shaped attaching member for linking said pull tab to said slider body, a locking finger, and a flat spring; said attaching member extending along one shield of the slider body and comprising two side walls extending in the longitudinal direction of said slider body and a transverse wall connecting said side walls, said locking finger being integral with one of said side walls and extending therefrom beyond said one shield towards said other shield of the slider body, said flat spring being integral with and projecting from an end of said transverse wall and extended downwardly and entered in the channel of said shield connecting means at least a part of the length of said downwardly entered portion of said spring being bent inwardly and at an angle to and bearing against a side wall and the bottom of the channel into which it is entered, the spring being thereby preloaded and normally biasing and locking unit towards said one shield about its rocking connection and

thereby urging the free end of said locking finger towards said other shield, means operatively connecting said pull member with said attaching member and actuatable upon exertion of a pull on said pull member to move the free end of said locking finger away from said other shield against the biasing action of said spring.

5. An automatic locking slider for a slide fastener, comprising a slider body, a pull member for operating the slider, and a one piece locking unit; the said slider body having opposing shields, and means extending therebetween for connecting said shields in spaced relation to form a Y-shaped channel for the passage of opposing scoop carrying stringers of a slide fastener, a 15 guide channel extending downwardly in said shield connecting means, an upstanding lug at one end of said one shield of said slider body, cooperating means on said locking unit and upstanding lug for rockingly connecting said locking unit to said upstanding lug and thereby to said slider body, an arcuate channel formed on the upstanding lug; the said locking unit comprising an open-ended channel shaped attaching member for linking said pull tab to said slider body, a 20 locking finger, and a flat spring; said attaching member extending along one shield of the slider body and comprising two side walls extending in the longitudinal direction of said slider body and a transverse wall connecting said side walls, said locking finger being integral with one of said side walls and extending therefrom beyond said one shield towards said other shield of the slider body, said flat spring being integral with and projecting outwardly and downwardly from an end of said 25 transverse wall and being entered respectively in the channels of said lug and said shield connecting means, at least a part of the length of the downwardly projecting portion of said spring being entered in the channel of said shield connecting means being bent inwardly and at an angle to and bearing against a wall thereof, the 30 spring thereby being preloaded and normally biasing said locking unit towards said one shield about its rocking connection and thereby urging the free end of said locking finger towards said other shield, means operatively connecting said pull member with said attaching member and actuatable upon exertion of a pull on said pull member to move the free end of said locking 35 finger away from said other shield against the biasing action of said spring.

6. An automatic locking slider as claimed in

claim 4, wherein the cooperating means on said attaching member and on said slider body comprise a pair of flat extensions integral with and projecting longitudinally from the side walls at one end of the attaching member, and said slider body has opposing longitudinally extending channels into which said extensions are disposed for rocking movement.

7. An automatic locking slider as claimed in claim 5, wherein the cooperating means on said attaching member and on said connecting lug comprise a pair of flat extensions integral with and projecting longitudinally from the side walls at one end of the attaching member, and said connecting lug has on each side thereof longitudinally extending channels into which said extensions are disposed for rocking movement.

8. An automatic locking slider as claimed in claim 5 wherein an upstanding stopping lug is mounted on said one shield at the opposite end thereof, and wherein the cooperating means on said attaching portion and on said connecting lug comprise a pair of flat extensions integral with and projecting longitudinally from the side wall at one end of the attaching member, and said connecting lug has on each side thereof longitudinally extending channels into which said extensions are disposed for rocking movement, and wherein a second pair of extensions which are integral with and project from side walls at the opposite ends of the latter to cooperate with the stopping lug, whereby the latter limits the rocking movement of said attaching portion away from the one shield under exertion of a pull on said pull member against the biasing action of said spring.

VITÉSZLAV WEBER.
